Primary Examiner — Andrew T Nemeth(74) *Attorney, Agent, or Firm* — Shumaker & Sieffert, P.A.(57) **CLAIM**

The ornamental design for a display screen with animated graphical user interface as shown and described.

DESCRIPTION

FIG. 1 is a first image of a display screen with animated graphical user interface; and, FIG. 2 is a second image thereof.

A first appearance of the animated graphical user interface sequentially transitions between the images shown in FIGS. 1-2.

The process or period in which one image transitions to another image forms no part of the claimed design. The dashed lines in each figure illustrate portions of the display screen with animated graphical user interface that form no part of the claimed design.
